UNITED STATES PATENT OFFICE.

ALBERT J. LYONS, OF MILWAUKEE, WISCONSIN.

SHIPPING-TAG.

1,306,492.

Specification of Letters Patent. Patented June 10, 1919.

Application filed November 25, 1918. Serial No. 264,054.

To all whom it may concern:

Be it known that I, ALBERT J. LYONS, a citizen of the United States, and resident of Milwaukee, in the county of Milwaukee and State of Wisconsin, have invented new and useful Improvements in Shipping-Tags, of which the following is a description, reference being had to the accompanying drawings, which are a part of this specification.

10 The invention relates to a shipping tag to be attached to articles of merchandise for shipment and more particularly to a tag which may be readily used as a return receipt for the goods so that the shipper may know of the safe receipt of the goods and the date when received, the tag serving as a record of the shipment.

15 The invention further consists in the several features hereinafter set forth and shown in the accompanying drawings in which:

Figure 1 is a front view of the tag in the condition in which it is attached to the goods to be shipped;

20 Fig. 2 is a front view of the tag in the condition in which it is to be returned to the shipper;

25 Fig. 3 is a back view of the tag in the condition in which it is to be returned to the shipper; and

30 Fig. 4 is a section taken on the line 4—4 of Fig. 1.

Referring to the drawings, the numeral 5 designates generally the tag which on one side is provided with the address 6 of the consignee and the address 7 of the consignor, a space 8 being reserved for postage in case the article is sent by mail. On the back of the tag there are designations 9 of the various articles to be shipped and the consignor may fill in the numbers of these articles accompanying the tag as shown at 10 in Fig. 3. On the face of this tag the shipping number 11 is given and the word "Shipped" 12 with the date of shipment 13 to be filled in by the shipper opposite the word "Shipped." There is also on the back of the tag the word "Received" 14 with the line 14' upon which the consignee fills out the date of receipt of the goods and there is also the writing "Received by" 15 with the line 16 underneath for the signature of the consignee. There is also a place 17 for a return stamp so that the tag may be mailed back to the shipper.

In using the tag as a return receipt, it is necessary to obliterate the address, or a portion of the address, of the consignee and to accomplish this purpose I have provided a covering tab 18 which is folded medially of its ends and is secured at its ends to the tag 5 by means of an eyelet 19. A portion of the tab adjacent one end is notched as 20 in Fig. 1 so as to form a short connecting portion 21 which may be readily torn off from this end of the tab attached to the tag by the eyelet. Adjacent this notched portion are wings 22 which are normally folded in under this end of the tab and notches 23 are cut in the tab adjacent the wings 22. A slot 24 is cut through the tag. The words "Insert here" 25 and "Detach here" 26 and "Return to" 27, with their arrows, are directions for the consignee. There is also a statement on the back of this tag "When signed by receiver return to shipper."

75 In the use of this tag, the tab is secured in position as indicated in Fig. 1 and the directions on the face of the tag show that the goods are consigned from Richard Roe to John Doe & Company, at a certain address, 80 and the back of the tag shows the character and amount of the goods shipped, the shipping number and the date when shipped. As soon as the goods are received by John Doe & Company or his receiver, he is instructed by the designation "Detach here" 85 26 to break off the connecting portion 21 of the tab and to insert the end thus broken off into the slot 24, the wings 22 being then spread out as shown in Fig. 3 so as to secure 90 the tab in the position shown in Figs. 2 and 3. When so secured, the tab obliterates a portion of the address of the receiver and also brings into view the words "Return to" 95 with the direction arrow pointing to the shipper. The receiver also places the date of receipt of the goods on the line 14' and his name on line 16, puts a stamp on the space 17 and returns the tag to the shipper who then has a permanent record of the 100 shipment of the goods.

While the tab 18 has been shown as a narrow strip which will cover a part of the address of the receiver, it will be understood that the tab may be made larger in width 105 so as to completely cover the name and address of the receiver, if desired.

From the foregoing explanation, it will

be noted that the invention will greatly facilitate negotiations between the shipper and receiver.

What I claim as my invention is:

- 5 1. The combination with a shipping tag upon which the names and addresses of the shipper and receiver appear and the designations "Shipped," "Received" and "Received by," of a tab carried by the tag and 10 normally exposing the said addresses, and means for moving and detachably securing a portion of the tab to the tag to cover the address of the receiver to permit the return of the tag by mail as a receipt to 15 the shipper.
2. The combination with a shipping tag, having the addresses of the receiver and shipper thereon, of a tab secured at its ends to the tag, means permitting of severing one 20 end of the tab from the tag, and means for securing this severed end to the tag over the address of the receiver.
3. The combination with a shipping tag, having the addresses of the receiver and shipper thereon, of a tab having its ends 25 secured to the tag and a reduced portion

adjacent one end to permit severing of this end of the tab from the tag, said tag having a slot therein, and an interlocking connection between the severed end of the tag and the slot, the tag being so disposed as to cover the address of the receiver when the severed end is held in the slot. 30

4. The combination with a shipping tag, having the addresses of the receiver and shipper thereon, of a tab having its ends secured to the tag and a reduced portion adjacent to the tag and a reduced portion 35 adjacent one end to permit severing of this end of the tab from the tag, said tag having an intermediate slot and an interlocking connection between the severed end of the tab and the slot, said interlocking connection being formed by wing portions on each side of the severed end of the tab, and said wing portions being adapted to be folded 40 under the tab when the reduced portion of the tab is unsevered, the tab being so disposed as to cover the address of the receiver when the severed end is held in the slot. 45

In testimony whereof, I affix my signature.

ALBERT J. LYONS.
